Lewis Miller

UNITED STATES PATENT OFFICE.

LEWIS MILLER, OF RICHMOND, INDIANA.

IMPROVEMENT IN CORN-PLOWS.

Specification forming part of Letters Patent No. 175,251, dated March 28, 1876; application filed January 24, 1876.

To all whom it may concern:

Be it known that I, LEWIS MILLER, of Richmond, Indiana, have invented certain new and useful Improvements in Corn-Plows; and I hereby declare the following to be a full, clear description of the same, reference being had to the drawings which accompany this specification, forming a part of the same, and to the letters of reference marked thereon, in which—

Figure 1 is a perspective view of my improvement, and Fig. 2 is an elevation of the clutch-plate with the standard and hoe attached.

Like letters of reference represent like parts.

To enable those skilled in the art to make and use my said invention, I will proceed to describe the same.

The nature of my invention consists in the application to the beam of hinged arms, having a forward or a backward motion on the beam, and also a vertical motion, and held in any desired position by a set-screw; also, in the employment of circular plates connected with said hinged arms, by which the outer arm is secured to the said hinged arms, and by means of a slot in said circular plate a backward motion is allowed in connection with the vertical motion resulting from the hinged arm, as connected with the beam; also, in hinging the frame of the handles upon the beam in such a manner as to allow an independent lateral motion of the handles to any angle that may be desired.

In the drawings, in Fig. 1, A is a round shaft or beam. B B are ordinary handles, attached to the beam by clutch-couplings O O, clamped and retained in position by set-screws and nuts. By relaxing these screws the handles may be given any desired angle from a perpendicular position. The rear clutch-coupling is extended up to form supports C C for the handles, and these supports are provided with holes to allow the handles to be raised and lowered at will, these couplings also allowing a fore-and-aft movement of the handles on the

beam A. F F are shovels of ordinary construction, attached to standards G G, which are secured to arms D' D', and held in position by set-screws d d through the agency of circular plates E E, which connect the arms D' D' with corresponding arms D D, the latter being hinged upon the beam A, and thus allowing any degree of vertical motion to the said arms and to the hoes attached. The circular plates E E are each composed of two disks, one of which sustains the arm D, and its fellow sustains the continuous arm D'. A screw-bolt, i, with its nut, near the periphery, secures these plates to each other, and a circular slot in one plate, corresponding with a hole in the other plate, said hole being supplied with a pin of wood or other suitable material, allows a swinging motion backward and upward of the standard G, whenever the hoe F meets any obstruction with force sufficient to break the pin. This is illustrated by the dotted lines in Fig. 2, in which the slot, the standard, and the hoe are fully shown.

It will be seen that, by means of the compound motion of the arms D and D', any desirable angle can be obtained for the hoes, both vertical and horizontal. Both hoes can be set to run in one furrow, or only one hoe used, or both may be detached and a "bull-tongue" or subsoil plow attached. The standards G G are round and fitted into the arms D', where they are held in any desired angle by means of set-screws.

Having thus fully described my said invention, what I claim is—

1. The arrangement and combination of the arms D D, circular plates E, slot E', and arms D' D', in the manner and for the purpose set forth.

2. The clutches O O, braces C C, and handles B B, in combination with the beam A, as herein set forth:

LEWIS MILLER.
